UNITED STATES PATENT OFFICE.

CHESTER T. DRAKE, OF CHICAGO, ILLINOIS.

APPARATUS FOR MIXING CONCRETE.

SPECIFICATION forming part of Letters Patent No. 699,668, dated May 13, 1902.

Application filed November 18, 1901. Serial No. 82,729. (No model.)

To all whom it may concern:

Be it known that I, CHESTER T. DRAKE, a citizen of the United States, residing at Chicago, county of Cook, State of Illinois, have 5 invented a certain new and useful Improvement in Apparatus for Mixing Concrete; and I declare the following to be a full, clear, and exact description of the invention, such as will enable others skilled in the art to which it 10 pertains to make and use the same, reference being had to the accompanying drawings, which form a part of this specification.

My invention relates in general to machines for mixing concrete, and more particularly to 15 conveyers for receiving the concrete from the mixer and delivering the same to any desired point where it is to be used.

In machines of the class mentioned in order 20 that the concrete may be delivered directly from the mixer to the place of use it is necessary to provide a conveyer capable of a horizontal movement around its point of connection with the mixer and also capable of a vertical movement in order to elevate its 25 delivery end to the desired height. It is essential that the mixed concrete should be deposited at all times by the mixer upon the adjacent end of the conveyer in whatever adjusted position it may be and also that the 30 conveyer should be so constructed that the mixed concrete will be carried to the desired point and there delivered in its mixed condition.

The object of my invention is to provide a 35 concrete-mixer with a horizontally and vertically movable conveyer driven by power communicated thereto in the axis of the king-bolt around which the conveyer is pivoted, the conveyer-belt being so guided as to be depressed at its longitudinal center and being 40 provided with a funnel-shaped hopper at its delivery end, thereby preventing the ingredients of the mixed concrete from being separated by centrifugal force as it passes from 45 the delivery end of the conveyer.

A further object of my invention is to provide a conveyer for delivering the concrete or other compositions from a mixer which will be simple in construction and efficient in 50 operation.

My invention will be more fully described

hereinafter with reference to the accompanying drawings, in which the same is illustrated as embodied in a convenient and practical form, and in which—

55

Figure 1 is a view in elevation of the conveyer and a portion of the mixer; Fig. 2, a plan view of the conveyer and the portion of the mixer to which it is connected; Fig. 3, a transverse section taken on line 3 3, Figs. 1 60 and 2; Fig. 4, a transverse section taken on line 4 4, Fig. 2; Fig. 5, a perspective view of the bearing-plate upon which the conveyer turn-table is rotatably supported; and Fig. 6, a transverse sectional view taken on line 65 6 6, Figs. 1 and 2.

Similar reference characters are used to indicate the same parts in the several figures of the drawings.

Reference characters A A indicate the side 70 frames of a support upon which the mixer C is mounted by means of braces a a, secured to and extending above the side frames A A and fixed at their upper ends beneath the horizontally-extending flange c at the top of 75 the mixer C. Mixing-blades C' are located within the mixer-tank and are secured to a shaft c', which is rotated by any suitable power connection. The support for the mixer may be rendered portable by means of wheels 80 B, located beneath the side frames and supporting the same by any suitable means—as, for instance, the braces a'.

Depending U-shaped frames A' and A², 85 preferably formed of channel-iron, are secured at their upper ends to the side frames A A near the delivery end of the mixer.

The horizontal portions of the depending frames A' and A² support beams A⁴, A⁵, and A⁶, which are preferably made of channel-iron opening downwardly, with the hollow portions thereof filled with hard wood, as indicated at a⁴ a⁵ a⁶. The outer beams A⁴ and A⁶ may be conveniently cut away at their ends so as to incline toward the center beam. 95 Secured to the beams A⁴, A⁵, and A⁶ is a plate A⁷, upon which is secured a ring E⁴ and concentric therewith a disk E², having a depression therein e², as shown in detail in Fig. 5. Mounted upon the ring E⁴ is a similar ring 100 E³, and superposed on the disk E² is a disk E', having a projecting portion fitting within

the depression e^2 in the disk E^2 . The ring E^3 and disk E' are rigidly secured to a plate D , preferably rectangular in shape, upon the upper surface of which are supported beams D' and D^2 , which are preferably arranged parallel and located at the opposite sides of the plate D . A king-bolt E passes through the centers of the disks E' and E^2 and also through the plates D and A^7 and is provided with a nut engaging the filling material a^5 of the channel-beam A^5 , through which the king-bolt also passes.

Secured to the upper surfaces of the beams D' and D^2 are brackets f^f , supporting at their upper ends a chute F , which is located immediately below the outlet C^2 of the mixer C .

The outer ends of the beams D' and D^2 are provided with circular depressions in which are located tubular extensions g' and g^2 , secured to the corresponding ends of the side frames G' and G^2 , which constitute the conveyer-frame. Straps d' and d^2 are secured to the upper surfaces of the beams D' and D^2 and retain the tubular extensions g' and g^2 within the bearings formed therefor. A series of guide-rollers H are located upon rods h , the outer ends of which are journaled in brackets g , secured to the upper surfaces of the side frames G' and G^2 . At each end of the guide-rollers H are located conical guides H' , which are rotatably supported upon the rods h by means of the integral sleeves h' .

A roller K is rotatably supported in the outer ends of the side frames G' and G^2 and is preferably journaled in adjustable bearings k . Guide-rollers $H^2 H^2$ are journaled in brackets depending from the under surfaces of the side frames. A funnel-shaped hopper L is located below the end of the conveyer-frame, to which it is secured by straps l . The outlet of the hopper is preferably provided with a swinging cover L' .

Bifurcated brackets $m' m'$ are secured to the side frames G' and G^2 and serve as bearings between which is supported a pulley M' , around which a rope M passes, the opposite ends of such rope being secured to means extending above the support for the mixer, whereby the rope may be wound up and the elevation of the conveyer-frame regulated. The means of winding up the rope M for convenience I have shown as consisting in a roller M^4 , mounted within uprights $A^3 A^3$, secured at their lower ends to the side frames G' and G^2 of the mixer-support. One end of the rope is rigidly secured to the uprights A^3 , while the other end is secured to the roller M^4 , above mentioned. The roller M^4 is provided with a gear-wheel M^2 , which is in mesh with a smaller gear-wheel M^3 , which may be rotated by means of a crank m^3 .

A power-shaft N is rotatably supported beneath the mixer and is provided with a beveled gear-wheel n at a point adjacent to a depending post N' , in the lower end of which the power-shaft is journaled. A double-faced beveled gear O is located above the king-bolt

E , with its axis in alignment therewith. I have shown such double-faced gear-wheel as mounted upon a short vertical shaft O' , the lower end of which is secured within a recess in a casting O^2 . The casting O^2 is provided with a recess in its under surface which fits over the head of the king-bolt and is provided with a projecting flange whereby it is secured to the plate D . The double-faced gear O is provided with collars o , which surround the end of the stub-shaft O' and permit the gear to freely rotate thereon. The teeth on the upper face of the gear O mesh with the gear n on the end of the power-shaft N , while the teeth on the under surface of the double-faced gear O are in mesh with a gear p , secured to the inner end of a short shaft P , which is journaled in a tubular bearing P' , attached to the vertical face of the beam D^2 . The end of the shaft P opposite to the gear p is provided with a sprocket-wheel P^2 , around which passes a sprocket-chain Q^2 . A shaft R extends through the tubular extensions g' and g^2 on the side frames G' and G^2 and is provided with bushings $r r$, interposed between the shaft R and the interior of the tubular extensions g' and g^2 . A sprocket-wheel R^2 is located on one end of the shaft R and is engaged by the sprocket-chain Q^2 . A sprocket-chain Q' engages a sprocket-wheel R' , secured to the other end of the shaft R , and a sprocket-wheel K' , secured to the reduced end of the roller K , which projects through the side frame G' .

A roller K^2 is provided with reduced ends which are journaled upon the upper surfaces of the beams D' and D^2 in the rear of the shaft R . Keeper-plates $k^2 k^2$ are secured over the journals of the rollers K^2 to retain them in their bearings.

The operation of my machine is as follows: The mixed concrete is delivered by means of the rotatable mixing-arms C' through the outlet C^2 to the chute F , which extends over the inner end of the conveyer-belt G . The endless conveyer-belt G passes around the idle roller K^2 at one end and around the driven roller K at the other end. The top portion of the conveyer-belt is supported by the rollers $H^2 H^2$, &c., while the under or returning portion of the belt is guided by the rollers $H^2 H^2$. The elevation of the conveyer-frame is regulated by winding up one end of the rope M by means of the windlass. The conveyer-frame is then swung horizontally about the king-bolt E to the desired position where the concrete is to be used. The rotation of the power-shaft N through the interposed gearing rotates the double-faced gear O , which in turn rotates the shaft P through the meshing gears, and the shaft P rotates the shaft R through the connecting sprocket wheels and chain. The rotation of the shaft R through the sprocket-wheels R' and K' and sprocket-chain Q' rotates the roller K , which drives the conveyer-belt G through frictional contact therewith. The weight of the concrete de-

presses the central portion of the conveyer-belt, the outer edges of which engage the conical rollers H' H'', thereby avoiding any danger of the concrete falling over the side edges

5 of the conveyer. The funnel-shaped hopper L receives the concrete from the end of the conveyer-belt and prevents the heavy ingredients of the concrete from being separated from the lighter ingredients, all of the con-
10 stituent parts of the concrete being received by the enlarged opening in the top of the hopper and concentrated by means of its reduced outlet. The cover L' may be swung into position to close the hopper, as indicated in
15 Fig. 1, when the concrete is being delivered into wheelbarrows, which are intermittently located beneath the hopper.

The location of the double-faced gear O in vertical alinement with the king-bolt permits
20 the power to be uniformly communicated from the power-shaft to the conveyer regardless of the horizontal adjustment of the conveyer-frame. The location of the shaft R concentrically within the pivotal connections
25 between the conveyer-frame and side beams D' D² permits the vertical adjustment of the conveyer-frame without affecting the engagement between the sprocket-wheels R' R² and the sprocket-chains Q' Q².

30 While I have described more or less precisely the details of construction, I do not wish to be understood as limiting myself thereto, as I contemplate changes in form, the proportion of parts, and the substitution
35 of equivalents as circumstances may suggest or render expedient without departing from the spirit of my invention.

Having now fully described my invention, what I claim as new, and desire to secure by
43 Letters Patent, is—

1. In an apparatus of the character described, the combination with a mixer, of longitudinal parallel beams upon which the mixer is supported, beams secured to and depending from said longitudinal beams, a horizontal frame supported beneath the discharging end of the mixer by said depending beams, and a conveyer mounted upon said horizontal frame.
2. In an apparatus of the character described, the combination with a mixer, of longitudinal parallel beams upon which the mixer is supported, beams secured to and depending from said longitudinal beams, a horizontal frame supported beneath the discharging end of the mixer by said depending beams, a turn-table rotatably mounted upon said horizontal frame, and a vertically-swinging conveyer pivotally secured to said turn-table.
3. In an apparatus of the character described, the combination with a mixer, of a support therefor, a discharge-chute located beneath the delivery end of said mixer and mounted upon said support, a cylindrical guide-roller journaled upon said support beneath said chute, a conveyer-frame pivotally

mounted on said support, a cylindrical guide-roller journaled in the outer end of said frame, concave guide-rollers journaled in said conveyer-frame, a conveyer-belt passing around 70 said cylindrical and concave guide-rollers, and a funnel-shaped hopper supported by said conveyer-frame below the cylindrical guide-roller journaled in the end thereof.

4. In an apparatus of the character de- 75 scribed, the combination with a mixer, of a support therefor, a horizontally-swinging conveyer-frame mounted upon said support, a conveyer-belt carried by said frame, and a chute horizontally movable with said conveyer-frame and receiving the material from the mixer and depositing the same upon the conveyer-belt, substantially as described.

5. In an apparatus of the character de- 85 scribed, the combination with a mixer, of a support therefor, a horizontally-swinging conveyer-frame mounted upon said support, a conveyer-belt carried by said frame, a chute horizontally movable with said conveyer-frame and receiving the material from the 90 mixer and depositing the same upon the conveyer-belt, and concave guide-rollers journaled in said conveyer-frame over which said belt passes, substantially as described.

6. In an apparatus of the character de- 95 scribed, the combination with a mixer, of a support therefor, a horizontally-swinging conveyer-frame mounted upon said support, a conveyer-belt carried by said frame, a chute horizontally movable with said conveyer-frame and receiving the material from the mixer and depositing the same upon the conveyer-belt, concave guide-rollers journaled in 100 said conveyer-frame over which said belt passes, and a funnel-shaped hopper supported by said conveyer-frame below the delivery 105 end thereof, substantially as described.

7. In an apparatus of the character de- 110 scribed, the combination with a support, of a vertically-swinging conveyer-frame mounted on said support, a conveyer-belt carried by said frame, transversely-extending sleeves secured to the sides of said frame, bearings on said support within which said sleeves are received, a shaft extending through said 115 sleeves, bushings secured to said shaft and interposed between the same and said sleeves, means for rotating said shaft, and means connecting said shaft with said conveyer-belt for driving the latter, substantially as described. 120

8. In an apparatus of the character de- 125 scribed, the combination with a support, of a horizontally-swinging conveyer-frame, a conveyer-belt carried by said frame, a turn-table mounted upon said support to which said conveyer-frame is connected, a king-bolt passing through said support and said turn-table, a gear-wheel the axis of which is in alinement with the king-bolt, a support for said gear-wheel secured to said turn-table and inter- 130 posed between said gear-wheel and king-bolt, a power-shaft operatively connected with said

gear-wheel, and means connecting said gear-wheel with said belt whereby the latter is driven, substantially as described.

9. In an apparatus of the character described, the combination with a support, of a horizontally-swinging conveyer-frame, a conveyer-belt carried by said frame, a turn-table mounted on said support to which said conveyer-frame is pivoted; a king-bolt passing through said support and said turn-table, a double gear-wheel having teeth on its upper and lower faces the axis of which is in alignment with said king-bolt, a power-shaft hav-

ing a gear-wheel in mesh with the teeth on one face of said double gear-wheel, a stub-shaft having a gear-wheel in mesh with the teeth on the other face of said double gear, and means connected to said stub-shaft for driving the conveyer-belt, substantially as described.

In testimony whereof I sign this specification in the presence of two witnesses.

CHESTER T. DRAKE.
